UNITED STATES PATENT OFFICE

2,095,384

HAMPER

Harold Gleitsman, Cedarhurst, N. Y.

Application October 22, 1936, Serial No. 106,939

5 Claims. (Cl. 217—122)

This invention relates to hampers and more specifically to clothes hampers.

In general, it is an object of the invention to provide a device of the character described, which will efficiently perform the purposes for which it is intended, which is simple and economical of construction, which can be expeditiously, conveniently and safely manipulated, and which can be readily manufactured and assembled.

10 Another object of the invention is to provide a hamper which segregates wet and dry clothes until they are all dry; to provide a hamper which supports wet clothes in the air to dry without the normal functions of the hamper, the receiving and containing of clothes, being interfered with; and to provide a hamper with such drying elements which may, when their usefulness in drying is no longer desired, be availed of as a handle or handles, with or without change of position.

15 Other objects of the invention will in part be obvious and will in part appear hereinafter.

The invention accordingly comprises an article of manufacture possessing the features, properties and the relation of elements which will be exemplified in the article hereinafter described and the scope of the application of which will be indicated in the claims.

20 For a fuller understanding of the nature and objects of the invention, reference should be had to the following detailed description, taken in connection with the accompanying drawings, in which:

Figure 1 is a perspective view of a portion of a device embodying one form of the invention;

25 Fig. 2 is a view, in elevation, partly in section, of a part of the device shown in Fig. 1;

Fig. 3 is a cross-section of the device shown in Fig. 2 taken along the lines 3—3; and

30 Figs. 4, 5 and 6 are perspective views of modifications of the device shown in Fig. 1.

In using a container as a receptacle for objects, it is often desirable and even necessary that there be a choice made among the objects. Certain ones may, in accordance with a predetermined arrangement, be placed in a container after certain other ones. It may be best to withhold some, either temporarily or indefinitely, so that they are not put into the container, at least at once. This is especially the case when the

35 container is a device in the nature of a clothes hamper. Sometimes, colored clothes or flat linen of a particular type should be kept separate so that the various kinds of clothes will not go to the laundry together. Also, wet clothes should not be placed in a hamper, either by themselves

or with dry clothes, until they have been given an opportunity to lose some of their moisture. It is not necessary that there be more than one hamper if means are present which permit such an assortment. It is desirable that a single hamper be sufficient to accomplish this as it is moved about.

It is contemplated by the present invention to accomplish such preliminary sorting or drying with a hamper which may be carried from place to place.

10 In the drawings, 10 denotes a hamper which may be made of any suitable material such as wicker-work, wood or metal. Associated with the top of the device and preferably along an upper periphery thereof, there are one or more handles 12. These handles are so installed that they may be moved with respect to the hamper and so that at least one end may be extended away from the side wall of the hamper and preferably in a direction horizontally away. Various means are 15 provided for accomplishing this. The handle may be pivoted at one end by means of a pivot 14 which is attached to the hamper. Where the handle 12 is closely adjacent the top of the hamper wall, the latter may have a portion cut 20 away as at 16 to provide a place for the hand of the person who is picking the hamper up.

25 The handle 12 may extend the entire length of one wall or only a portion of the length of a wall. There may be a plurality of handles along any one wall, each pivoted at one end. Their free ends may come together as in Fig. 2. When such handles are in alignment and with their free ends adjacent, they are available to be used separately or together as a single unit.

30 The handles and their pivots may be attached to a rim 18 on the top of a hamper wall. The rim may extend up over the pivot and even along and above the handle to act as a kind of guard 20. There may be decorative devices 22 on the guard. 35 One of these is shown in Fig. 1 as cut away so as to expose, for the purposes of this description, the end of the pivot pin 24.

30 The temporary support may be positioned below the top of the hamper in a recess 26 in a wall 45 of the hamper. This form is particularly suitable where that wall or that portion of the wall is made of metal (see Fig. 4). The supporting element 12 may be pivoted in the slot 26 on pivot 14.

40 In Fig. 5, there is shown a pair of handles 12 without the guard 20, each pivoted in a bracket 28 conveniently positioned along the top of the hamper. The end of each handle 12 may have a knob 30 or other latching element, which catches into a corresponding latching element 32 45 50 55

fixed to the hamper. The element 32 may receive some of the stress due to the weight of the hamper and its contents as the hamper is moved from place to place and so permit the bracket 28 and pivoting means to be of somewhat less heavy construction. A single such arrangement may take the place of the double arrangement shown.

The motion of the supporter may be brought about by having it slide with respect to the hamper wall, as shown in Fig. 6. There, the support or handle 12 lies in a longitudinal slot 34 which is open at one or both ends. The support 12 is slid able in the slot and has means for holding it in one or more particular positions and means 15 for preventing it from falling entirely out of the slot. These means may include an enlarged knob 36 on the end of the support or handle. A button on the end of a spring affixed on the interior of the slot may register with an indent in 20 the knob.

It is intended that the present device should be such that it may be picked up by the handle 12 and moved from one position to another and that when it is set down, the handle may be pivoted to slide away from the body of the hamper basket and support any wet clothes which may need to be dried as long as is necessary.

Since certain changes may be made in the above article and different embodiments of the 30 invention could be made without departing from the scope thereof, it is intended that all matter contained in the above description or shown in the accompanying drawings shall be interpreted as illustrative and not in a limiting sense.

35 It is also to be understood that the following claims are intended to cover all of the generic and specific features of the invention herein described, and all statements of the scope of the

invention which, as a matter of language, might be said to fall therebetween.

Having described my invention, what I claim as new and useful and desire to secure by Letters Patent is:

5 1. In a device of the character described, the combination comprising a container adapted to receive objects, and handle means pivoted on said container and having a portion adapted to swing free from said container and to support one of 10 said objects, said means comprising a straight bar pivoted at its end.

15 2. In a device of the character described, the combination comprising a container adapted to receive objects, and a plurality of handle means 15 pivoted on said container and each having a portion adapted to swing free from said container and to support one of said objects, said plurality when in use as a handle being positioned as linear extensions of each other.

20 3. In a device of the character described, the combination comprising a container adapted to receive objects, and handle means adapted to be used together as a handle and pivoted independently about vertical different axes.

25 4. In combination, a clothes hamper having a side wall, said side wall having a recess in the upper portion thereof, supporting means pivotally attached to said hamper and adapted to be received into said recess and to be moved to 30 support clothes away from said hamper.

35 5. In combination, a clothes hamper having a side wall, said side wall having a recess in the upper portion thereof, supporting means movably attached to said hamper and adapted to be received into said recess and to be moved to support clothes away from said hamper.

HAROLD GLEITSMAN.
